UNITED STATES PATENT OFFICE

2,608,804

ABRASIVE POLISHING WHEEL

Henry M. Field, Dayton, Ohio

Application March 6, 1950, Serial No. 147,866

4 Claims. (CL. 51—193)

1

This invention relates to abrasive polishing wheels.

An object of this invention is to provide an abrasive polishing wheel which is polygonal in front elevation and is so designed that the abrasive action is produced by the corners of the wheel, and as the corners wear down successive new corners are brought into operation.

Another object of this invention is to provide an abrasive wheel which is formed of right angularly disposed interlaced or interlocked abrasive strips which may be held together by means of adhesive or other securing means.

A further object of this invention is to provide an abrasive wheel which is formed of laminated layers of abrasive material which are interlaced together so as to provide progressively usable abrasive surfaces as the outer surfaces wear down.

With the above and other objects in view, my invention consists in the arrangement, combination and details of construction disclosed in the drawings and specification, and then more particularly pointed out in the appended claims.

In the drawings:

Figure 1 is a detailed front elevation of an abrasive polishing pad or element constructed according to an embodiment of this invention.

Figure 2 is an end elevation of this device.

Figure 3 is a sectional view taken on the line 3—3 of Figure 1.

Figure 4 is a plan view partly broken away showing the manner in which the abrasive strips are initially secured together and interlaced.

Figure 5 is a view similar to Figure 4 showing the abrasive faces of the strips.

Figure 6 is a front elevation showing a modified form of this invention.

Figure 7 is a fragmentary sectional view taken on the line 7—7 of Figure 6.

Figure 8 is a fragmentary front elevation of another modification of this invention.

Referring to the drawings, and, first, to Figures 1 to 5, inclusive, the numerals 10 and 11 designate generally a pair of elongated abrasive strips having a fabric base. The abrasive strips 10 and 11 are initially secured together in overlapping relation and at right angles to each other as shown in Figures 4 and 5 with the abrasive faces of the strips on the same sides. The strips 10 and 11 are then alternately overlapped one upon the other so as to interlace the strips and in the final overlapping of the strips, the end of the strip 10 will terminate as shown in Figures 2 and 3 at a point inwardly from the marginal edges of the pad formed thereby. The pad generally designated as 12 which is formed by the interlacing of the

strips 10 and 11 together will be of substantially polygonal form as shown in Figure 3 with cutouts 13 at each corner.

In the interlacing of the strips together, the 5 marginal or outer edges of the pad formed by the overlapping and interlacing of the strips will form a convex transversely curved marginal edge 14. Where the pad is of relatively large size, a core or sleeve 15 is extended centrally through aligned 10 openings 16 which are formed in the overlapping portions of the strips, and a mandrel 17 is extended through the sleeve or core 15.

In the construction shown in Figures 1 to 5, inclusive, the terminal end portion of the abrasive strip 10 may be secured to the adjacent portion of the strip 11 by adhesive 18 or the like. If desired, the several folds or overlapping portions of the abrasive strips may be securely fastened together by adhesive so that the central body portion of the pad will be relatively solid; whereas the outer marginal portions of the pad will be of cushioned characteristic.

Referring now to Figure 6, there is disclosed a modification of this invention wherein abrasive strips 10a and 11a are interlaced together after the manner shown in Figures 1 to 5, inclusive. The pad 12a shown in Figure 6 is relatively thinner than the pad shown in Figure 3, and in this instance a piece of adhesive tape 19 is wrapped about the terminal end of the abrasive strip 10a and engages about the overlapping or laminated portions of the strips 10a and 11a. Preferably the adhesive securing member 19 is disposed inwardly from one marginal edge of the pad so that the adhesive tape or strip will not be torn during the use of the pad.

Referring now to Figure 8 there is disclosed another modification of this invention wherein the abrasive strips 10b and 11b are disposed in overlapping and interlaced position. In the present instance, however, the strips 10b and 11b have a folded length substantially greater than the width of the strips so as to thereby form a pad of substantially cross shape. The pad shown in Figure 8 will provide a pad which has slightly greater cushion characteristics than the pads shown in Figures 1 to 6, inclusive.

In the use and operation of this abrasive pad, the mandrel 17 is extended through the center of the pad and secured thereto by means of a nut 20. The pad is then rotated with the corners of the pad engaging the work, and as the corners of the pad wear down, the outermost turns of each strip will wear off and the succeeding turns or folds of the strip will be rendered effective.

What is claimed is:

1. An abrasive polishing element comprising a pair of elongated transversely folded abrasive strips interlaced together at right angles to each other, the length of the folded portion of each strip being substantially greater than the width of the strip whereby the pad formed by said strips will be of cruciform shape.

2. An abrasive pad comprising abrasive coated sheet material folded upon itself to form a plurality of plies, adhesive means binding said plies together into a flat pad having angular corners there being a centrally located aperture in said pad.

3. An abrasive pad comprising two strips of abrasive coated sheet material arranged at right angles to each other and folded in plies upon each other to form an X-shaped flat pad with radially extending arms, the plies of said pad being adhesively bonded together and said pad having an aperture through the center thereof.

4. An abrasive pad comprising two strips of

abrasive coated sheet material arranged at right angles to each other and folded in plies upon each other to form an X-shaped flat pad with radially extending arms, the plies of said pad being adhesively bonded together and said pad having an aperture through the center thereof, and a bushing disposed in said aperture.

HENRY M. FIELD.
